UNITED STATES PATENT OFFICE.

CHARLES A. HORN, OF CHICKASHA, OKLAHOMA.

ICE-SHAVER.

1,107,070.

Specification of Letters Patent.

Patented Aug. 11, 1914.

Application filed July 2, 1913, Serial No. 776,968. Renewed June 22, 1914. Serial No. 846,502.

To all whom it may concern:

Be it known that I, CHARLES A. HORN, a citizen of the United States, and a resident of Chickasha, in the county of Grady and State of Oklahoma, have made certain new and useful Improvements in Ice-Shavers, of which the following is a specification.

My invention is an improvement in ice shavers and consists in certain novel constructions, and combinations of parts hereinafter described and claimed.

The object of the invention is to provide a device of the class described, which will be simple in construction, efficient in operation, and one which may be manufactured at a small cost.

Referring to the drawings forming a part hereof, Figure 1 is a longitudinal section of the improvement, Fig. 2 is a similar view showing the parts in another position, Fig. 3 is a perspective view of one end, and Fig. 4 is a front view of the blade.

The embodiment of the invention shown in the drawings consists of a receptacle or box having a bottom 1, sides 2 and a rear end 3, and a cover 4 for the top and front end of the receptacle is provided, the cover being hinged to the rear end wall 3 in a manner to be presently described.

30 A transverse slot 6 is arranged in the bottom adjacent to the rear end wall, and a blade 7 is slidably mounted on the front face of said wall, the edge 8 of the blade projecting through the slot, a sufficient distance to secure a good cutting action. The blade is provided with three parallel vertical slots 9—10 and 11, the central slot 10 being of greater length than the side slots as shown, and the rear wall 3 is provided 40 with similar slots 12—13 and 14 registering with the slots of the blade.

Bolts 15 pass through the registering side slots and are engaged by nuts 16, for retaining the blade in adjusted position, and 45 the heads of the bolts are screw heads as shown. It will be evident that by loosening the nuts the blade may be adjusted on the rear wall to project more or less of the blade.

The cover is provided with bearings 5 at 50 each of its rear corners, and in the bearings is secured a shaft or rod 17, whose extended ends 18, are journaled in bearings 19 on the end wall. An arm 20 is rigidly connected with the center of the shaft and projects 55 rearwardly therefrom. A plate or plunger 21 is slidable in the box, the plate being ar-

ranged transversely of the box and having a beveled lower edge 22, and an arm 23 is rigidly connected with the center of the plate and extends rearwardly through the 60 registering central slots 10 and 13, to a pivoted connection with the end of the arm 20 as at 24. The arm 20 is provided with an upwardly extending lug 25, and the arm 23 with a similar lug 26, and a coil spring 65 27, having its ends hooked, and engaging openings in the lugs. It will be evident from the description of the construction, that when the cover 4 is lifted into the position shown in Fig. 2, the plate will be moved 70 toward the front end of the receptacle, and when the cover is closed, it will be moved toward the other end.

The operation of the device is as follows: The blade 7 being adjusted properly, the receptacle is moved over a block of ice with a planing action, and the slivers or shavings of ice pass into the receptacle. When a sufficient supply has been collected, the cover is elevated, and the contents of the receptacle 75 are pushed out at the front thereof. When the cover is closed the spring 27 is placed under tension, thus acting normally to retain the cover open, and the plate in its forward position. After the box is filled with 80 ice shavings, merely by releasing one's grasp of the box it is automatically opened by the spring.

It will be evident from the description, that the shaver shown and described is convenient and efficient and not liable to get out of order, and that it may be cheaply manufactured, there being no complicated parts. By the arrangement of the spring it is not necessary to provide a handle for the door, 95 and it cannot become jammed for the same reason.

I claim—

1. An ice shaver comprising a box having an open end and top, a transverse slot in 100 the bottom near the closed end, a blade adjustable on the said closed end and projecting through the slot, said blade and end wall having registering vertical slots, a cover hinged to the said closed end and closing the 105 box, an arm rigid with the cover, a plate arranged transversely of the box, an arm rigid therewith and extending through the registering slots the outer ends of the arms being pivotally connected, lugs on the arms, 110 and a spring connecting the arms, and normally acting to retain the cover in open po-

sition, and the plate at the open end of the box.

2. An ice shaver comprising a box having an open top and end, the bottom having a transverse slot near the closed end, a blade 5 adjustable on said closed end and projecting through the slot, a plunger movable longitudinally of the box toward and from the open end, a cover hinged to the closed end 10 for closing the box, arms pivotally connected at one end and rigidly connected by the other end with the cover and the plunger respectively, for moving the plunger toward the open end of the box when the cover is 15 opened, and a spring normally retaining the cover in open position.

3. An ice shaver comprising a box having an open top and end, the bottom having a transverse slot near the closed end, a blade 20 adjustable on said closed end and projecting through the slot, a plunger movable longitudinally of the box toward and from the open end, a cover hinged to the closed end for closing the box, a connection between the 25 cover and the plunger for moving said plunger toward the open end of the box when the cover is opened, and a spring for normally retaining the cover in open position.

4. An ice shaver comprising a box having 30 an open top and end, the bottom having a transverse slot near the closed end, a blade adjustable on said closed end and projecting through the slot, a plunger movable longitudinally of the box, a cover hinged to the 35 box for closing the same, a connection be-

tween the cover and the plunger for moving said plunger toward the open end of the box when the cover is opened, and a spring for normally retaining the cover in open position.

5. An ice shaver comprising a box having an open end, means in connection with the box for shaving the ice, a plunger for ejecting the shaved ice movable longitudinally of the box, a cover for the box, a connection 45 between the cover and the plunger for moving said plunger toward the open end of the box when the cover is opened, and a spring movably retaining the cover open.

6. In an ice shaver a plunger for ejecting the shaved ice, a cover for the box, a connection between the cover and the plunger for operating the same to eject the ice when the cover is opened, and a spring for normally retaining the cover in open position.

7. An ice shaver comprising a box having its top and one end open, a cover for closing the open top and end, means movable longitudinally of the box for ejecting the shaved 60 ice, a connection between the cover and the ejecting means for causing the said means to eject the ice when the cover is open, and a spring arranged between the cover and the ejecting means for returning the parts 65 to their normal position.

CHARLES A. HORN.
